METHOD FOR PREVENTING AND REMOVING
ACCUMULATIONS OF FOREIGN MATERIALSNoble C. Smith, Larkspur, Calif.; Frank J. Keaton,
special administrator of said Noble C. Smith,
deceased, assignor to Yosemite Chemical Co.No Drawing. Application November 7, 1947,
Serial No. 784,759

7 Claims. (Cl. 134—4)

1

This invention relates to a method for preventing and removing rust, scale, dirt, marine growth, etc. from various surfaces and more particularly to a method which utilizes emulsifying agents for such purposes.

The present method has been specifically designed to overcome many of the difficulties which have been inherent in processes disclosed in the prior art. These difficulties may be divided into two general classes, one concerned with the problem of application of the preventative or remover and the other with the problem of insuring that all foreign material is completely removed.

With regard to insuring removal of all foreign material, the prior art has generally depended upon a dissolving action of one kind or another by means of which the foreign material is broken down, either physically or chemically, so that it may be easily carried away. But basically, these methods have in common the requirement that the bond between the surface to be cleaned and the foreign material must be either dissolved or chemically changed. The present method appears not to be dependent upon this phenomenon, but rather relies on the swelling characteristic of an emulsion or gel to mechanically break the foreign material from the surface. In other words, the emulsifying agent causes the formation of a gel between the surface and the foreign material and its inherent expansion mechanically loosens the latter. An emulsifying agent of opposite characteristics may then be applied to reduce the gel and cause the foreign material adhering to it to drop off.

The above discussion has been primarily concerned with how the present invention actually operates. The second important aspect is the method herein disclosed for applying the emulsifying agents. Although the agents could, of course, be applied by painting, washing, spraying or other conventional methods, these are not the most satisfactory methods for use on large enclosed areas. For example, in a marine drydock, very large compartments are utilized to raise and sink the dock by a process of filling and emptying the same. These are usually filled from the bottom with sea water and as a consequence, the present invention utilizes an agent which will float upon the water and is thus carried up and down on the water's surface, coating the sides of the compartment as the water level rises and falls. It is to be noted that the agents are not interspersed or mixed throughout the volume of the water, but form a layer at its surface; and also are not eliminated when the com-

2

partment is emptied. The agents floating on a shallow layer of water are left behind.

So far, the discussion has been concerned principally with the use of the process for cleaning or removal. The same principle may also be conveniently utilized as a preventative method. In view of the fact that an emulsion is an excellent barrier against the penetration of gases, water vapor, and other substances which tend to cause the formation of rust, scale, foreign material, etc., an agent of the type described above and with somewhat lesser emulsifying characteristics can be left permanently in the enclosed compartments, such as those described above, with excellent results. Thus, if the compartment is new or has already been cleaned, the provision of a layer of the agents on the water surface will effectively prevent the deposit of rust, scale and other foreign matter.

20 Although, as has been stated, the agents herein described may be applied in any convenient fashion, the process will be described herein as it is used in one of its primary applications, i. e., in marine dry docks.

25 As is well known, marine dry docks are comprised of one or more flotation compartments, alternately filled and emptied to permit submersions and liftings of the dock. The surrounding water is, of course, used in this process and repetitions of the filling and emptying procedure causes considerable amounts of rust and scale to form and the deposit of appreciable amounts of dirt and other foreign matter. Normally, dry docks are made of metal and these various deposits and the reaction with the metal are most undesirable to insure long life of the dock.

In the present instance, the process will be first described in conjunction with a dry dock which has been in use for some time and whose compartments show considerable evidence of rust, scale and the deposit of foreign material.

40 The removal of this material may be accomplished by first adding to each submersible compartment an emulsifying agent which herein will be called agent No. 1. Agent No. 1 is one which will cause the formation of a water-in-oil emulsion and is added while the dry dock is raised and the water level in the compartments is at the lowest point. Sufficient of agent No. 1 is added to form a layer of from $\frac{1}{2}$ " to $\frac{3}{4}$ " thick on the surface of the water.

45 As has been stated, agent No. 1 is one which produces a water-in-oil emulsion and may comprise one of the fatty acid or other organic acid soaps of a divalent metal such as calcium, bar-

ium, strontium, etc. Of course, it should be one which does not chemically react with metal, wood, etc. or other materials contained in or comprising the compartment. It also should preferably have high penetrating or polar characteristics which will cause the oil to displace water from the metal surface and from between the particles of rust, scale, etc. Although a heavy oil would be best as a diluent, diesel or stove oil is quite satisfactory. Thus, an acceptable example of agent No. 1 might comprise 5 parts (by weight) of a calcium soap, such as calcium lanolate, 2 to 3 parts pine oil and 100 parts diesel oil.

After agent No. 1 is added to the compartment, the water is permitted to flow into the compartment, as by normal sinking of the deck. As the level of the water rises, agent No. 1 will be deposited on the walls, bracing, etc. of the compartment as each area is successively submerged. The agent has a high penetrating characteristic and after one or more submersions, it will have been found to have worked its way into all cracks, spaces, blisters, and particularly in, through and behind the deposits of rust, scale and foreign matter. To insure better penetration and the coating of all areas, the dock may be rocked, if desired, but this is not always necessary.

In practice, after agent No. 1 has been added, it is preferably left alone for from 2 to 6 days, during which time the dock will presumably be raised and lowered several times. In any event, agent No. 1 soon begins to form an extremely rigid, water-in-oil emulsion or gel wherever it has been deposited. This viscous emulsion or gel (which terms are used interchangeably herein) has extremely stable qualities and is generally of the consistency of Vaseline and will not flow on a vertical surface. It forms not only on solid surfaces, but also tends to form a solid, jelly-like mass on the water surface.

Of course, during the formation of the gel, it exhibits its normal tendency to swell and, where deposited under or behind rust, scale or other foreign deposits, forces them to itself by adhesion. As far as is determinable, it is this mechanical phenomenon alone which causes the breaking away of the foreign material and it is not believed that any particular chemical reaction between the gel and the foreign material takes place. Naturally, too, through repeated submersions, additional layers of the emulsion are deposited, and each swelling in turn causes a further separation between the surfaces to be cleaned and the foreign material.

After the rigid emulsion or gel has completely formed and broken away the foreign material, agent No. 2 is added to the compartments. Agent No. 2 must be of such composition that it has a tendency to break down the already formed water-in-oil emulsion and must be oil soluble. Such materials as the phenols or sodium sulphonate of high molecular weight have been found extremely satisfactory, for example, a satisfactory agent No. 2 would comprise 5 parts (by weight) sodium sulphonate, 10 parts phenol and 100 parts diesel oil. Agent No. 2 is also preferably added when the water level is low and subsequent submersions of the dock cause it, like agent No. 1, to be deposited on all of the areas on which the water-in-oil emulsion has formed.

Agent No. 2 immediately begins to break down or reduce the water-in-oil emulsion. The gel structure is disrupted at least sufficiently that

the gel will drop or flow off the vertical surfaces carrying the foreign material with it. It is to be noted that agent No. 2 is added, depending upon its specific characteristics, in sufficient quantity to make the gel less viscous, but not sufficiently to reduce or invert the emulsion into an oil-in-water emulsion. In normal dry dock operation it may take from 4 to 5 days before the reduction process is complete. Its obvious purpose is to reduce the viscosity so that gravity flow and subsequent submersions are enabled to carry away the rust, scale and other foreign material which have been broken away from the surfaces and which adhered to the gel.

Thus, in the new process, the gel is first formed to break the foreign material from the surfaces to be cleaned and it is then reduced to permit the material to drop off or be carried away by subsequent submersions.

The method outlined above is obviously most satisfactory where the cleaning is to be done on surfaces in a closed container or system in which there is a periodic flow of liquid on which the agents may be floated. As has already been said, the same results may be accomplished by applying the agents and the necessary water by submersion, spraying, painting or other conventional methods. However, it is obvious that in those instances where a periodic flow of the system is present, the specific method described insures excellent and complete coatings of all surfaces with a minimum of time and expense. Even in closed systems where no periodic flow is had, such a method of flotation may well be utilized if dismantling of the system would be necessary to accomplish the coating.

Obviously, agents having stronger or lesser tendencies to form and reduce the gel may require different periods of time. The time for any given agents may be determined by observation, agent No. 2 being added when agent No. 1 has formed the viscous gel described above. The process is completed, after the addition of agent No. 2 when the gel has largely broken down, at which time it will be found that the cleaned areas are coated with a thin, white, creamy emulsion.

In the above description, it was assumed that the surfaces concerned were originally covered with rust, scale, etc., making a cleaning operation necessary. The use of both of the above agents was therefore necessary. However, once the surfaces have been cleaned, as by the above method or otherwise, or if the surfaces are new, they may be maintained in such condition by the use of agent No. 1 alone or by a single application of a combination of agents Nos. 1 and 2. This preventive feature of the invention depends upon the fact that an emulsion is an excellent barrier against gases, water vapor, etc. which cause rust and the adherence of other foreign material. Thus, if the surfaces to be protected are periodically coated with agent No. 1 or combination of agents Nos. 1 and 2 (either by conventional methods, or by the process described above in conjunction with a drydock), to form the water-in-oil emulsion, the surfaces will be thoroughly and permanently protected against formation or deposit of foreign materials.

The main distinction between the treatment accorded the surfaces in the cleaning process and in the preventive process is the elimination of the use of or separate application of agent No. 2. Agent No. 2 is required in the cleaning process to break down or reduce the rigid emul-

sion or gel formed by rather large amounts of agent No. 1. If this were not used, the gel formed on the water surface would be so thick that additional coatings would not be added by subsequent immersions and the material removed would remain adhering to the gel on the surfaces.

As a consequence, for preventive purposes, the necessary proportions of agents Nos. 1 and 2 could be added at the same time, or a weakened agent No. 1 could be used. For example, if the formula given above for agent No. 1 included considerably more of the calcium soap, the tendency to create a viscous emulsion or gel is greatly lessened, which is desirable in the preventive process. However, such dilution also cuts down on the protective characteristics afforded by the soap and it might then be necessary to add other waxes, asphalt, tars or heavy petroleum oils to increase the preventive characteristics. For this reason, it is more practical to use some of both agents Nos. 1 and 2, the combination of which, acting as a single agent, has the required emulsifying and preventive characteristics, and the desired white creamy emulsion is formed on the surfaces.

This creamy emulsion serves to adequately coat and protect the surfaces against the formation and deposit of foreign materials, and is of the same consistency as is produced finally in the removing process. In practice, of course, small amounts of the diluted agent No. 1 or the combination of agents Nos. 1 and 2 will be added from time to time as required in order to maintain said emulsion at all times.

I claim:

1. The process for removing material such as rust, scale and the like from a metal surface comprising the steps of: filling the interstices in said material and between said material and said surface with an emulsifying agent in oil, said agent comprising a fatty acid soap of a divalent metal automatically adapted to and capable of forming with water a water-in-oil viscous gel emulsion adapted to expand during its formation; providing the water to the agent so filling said interstices; permitting the formation of said gel emulsion in said interstices whereby its expansion during said formation will tend to loosen said material from said surface; thinning said gel with an oil soluble thinner capable of reducing the viscosity of the gel to facilitate its removal from said surface together with the material so loosened from said surface.

2. In the process for removing rust, scale, and the like from a metal surface on which any of such materials has formed that comprises the steps of: coating said surface with an emulsifying agent in oil and in the presence of water, said emulsifying agent being an organic soap of a divalent metal, said agent in oil thereafter automatically forming a water-in-oil emulsion and viscous gel on said surface after its application thereto in the presence of water; and thereafter reducing the viscosity of said viscous gel by applying an oil soluble thinner thereto after it has formed, said thinner being capable of reducing the viscosity of the already formed emulsion thereby causing said material to freely flow on said surface.

3. The process of removing material such as rust, scale and the like that is attached to metal on which it is formed from the surface of said metal comprising the steps of: depositing between said material and said surface a fluid con-

taining an organic soap of a divalent metal, said fluid having the property of forming an expandable, water-in-oil emulsion in the presence of water and providing the water for the formation of said emulsion whereby the expansion of the latter between said material and said surface will force the material from said surface, and thereafter reducing the viscosity of said emulsion by applying an oil soluble thinner thereto, said thinner being capable of reducing the viscosity of the already formed emulsion thereby causing said material and thinned emulsion to fall therefrom.

4. The process of removing material such as rust, scale and the like from a surface to which it is attached that comprises the steps of: floating on a body of water an emulsifying agent in oil and which agent in oil has the characteristic of forming in association with said water a water-in-oil emulsion and relatively viscous gel, said agent being an organic soap of a divalent metal, immersing such surface and material in said water below said agent and before the forming of said water-in-oil emulsion and then withdrawing said surface and said material through said agent whereby water and said agent in oil will be adhered to said surface and will enter any interstices in said material and between such material and said surface and will form said water-in-oil emulsion on said surface and in said interstices, then permitting the said formation of said water-in-oil emulsion in said interstices and on said surface, and thereafter substantially thinning the said emulsion with an oil soluble thinner, said thinner being capable of causing said emulsion and any of the said material therein to fall away from said surface.

5. The process for removing material such as rust and scale from the metal side walls of a container that comprises the steps of: providing a body of water against said walls, floating an emulsifying agent in oil on the surface of said body and in contact with said walls, said emulsifying agent being an organic soap of a divalent metal, having the characteristic of adhering to said walls together with water upon raising and lowering the level of said body and of forming a water-in-oil emulsion with said water after it has so adhered to said walls, raising and lowering the level of said body to cause said adherence and coating of said walls and the said formation of said emulsion on said walls, said emulsion having the further characteristic of being expandable during its formation whereby its said expansion between the metal surface of said walls and any of said material will force said material from said walls and into the emulsion coating said walls, then reducing the viscosity of said emulsion by applying an oil soluble agent thereto, said agent being capable of reducing the viscosity of said emulsion so that the emulsion and any of said material will fall from said walls.

6. The process for removing rust, scale, and other foreign material attached to a metal surface therefrom comprising the steps of: coating the metal to be cleaned with an oil containing a penetrating and emulsifying agent in the presence of water having the property of entering any of the interstices in the rust, scale, etc., and forming an expanding viscous gel emulsion therein, said emulsifying agent having a fatty acid soap of a divalent metal selected from the group consisting of calcium, barium, strontium and in the ratio of about 5 parts by weight of said calcium soap to about 2 to 3 parts by weight

of pine oil and about 100 parts by weight of petroleum oil, contacting the so coated metal with water so as to permit said emulsifying agent in said oil and in the presence of water to form said expanding viscous gel emulsion in said interstices and between the metal surface and said rust, scale and foreign material so the latter will be loosened from said metal under the expanding force of said emulsion, then reducing the viscosity of said gel by applying a second agent to the gel, 10 said second agent consisting of about 10 parts by weight of phenols and about 100 parts by weight of petroleum oil, such emulsion and said second agent remaining and being in contact with at least a portion of said metal.

7. In the process for preventing the accumulation of material such as rust, scale and the like on a clean metal surface, the steps of applying to the surface to be protected an oil containing an emulsifying agent, said agent having the property of forming a water-in-oil emulsion with said

oil containing said agent, said emulsifying agent being an organic soap of a divalent metal, applying water to said coated surface to effect the formation of said water-in-oil emulsion and subsequently recontacting said coated surface with water to maintain said water-in-oil emulsion.
